UNITED STATES PATENT OFFICE.

HARRY BRADLEY ROWAN, OF NORTH ATTLEBORO, MASSACHUSETTS, ASSIGNOR TO
WHITING & DAVIS COMPANY, A CORPORATION OF MASSACHUSETTS.

DESIGN FOR A MESH BAG.

Application filed July 28, 1922. Serial No. 3,230. Term of patent 7 years.

To all whom it may concern:

Be it known that I, HARRY BRADLEY ROWAN, a citizen of the United States, residing at North Attleboro, Bristol County, Massachusetts, have invented a new, original, and ornamental Design for Mesh Bags, of which the following is a specification, reference being had to the accompanying drawing, forming part thereof.

The figure is a front view of a mesh bag showing my new design.

I claim:

The ornamental design for a mesh bag as shown.

HARRY BRADLEY ROWAN.
